(57) CLAIM

The ornamental design for a corks cork holder, as shown and described.

DESCRIPTION

FIG. 1 is a front, left side and top perspective view of a corks cork holder showing my new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof; and,

FIG. 8 is a bottom, right side and back view thereof.

The broken lines depict portions of the corks cork holder that form no part of the claimed design.
